DES. 2034

Lewis Heathbone of Albany, N.Y.

Fitter's Patent No. 3634. Dated July 28, 1865.

Ornamental design for the plates of a Cooking Stove.

The Schedule referred to in these Fitter's Patent and making part of the same:

Be it known that I, Lewis Heathbone of the City of Albany, State of New York, have produced a new ornamental design for the plates of a Cooking Stove and I submit the annexed drawings (photographs) of the Euackal stove, so called, exhibiting in perspective a view with the plates in place, to be at full and exact delineation of the said plates with their ornaments. The oven and furnace doors not represented being symmetrically similar to those shown in the drawings.

What I claim as my production and desire to secure by Fitter's Patent is the combination and arrangement of figures and forms, above referred to represented in the accompanying drawings, forming together an ornamental design for the plates of a Cooking Stove.
